United States Patent

Des. 238,346

Patented Jan. 6, 1976

238,346

CLOCK FACE

Ronald Reginald Burgess, Phoenix, Michael Garm Coleman, Tempe, Lawrence Ames Grenon, Phoenix, and Israel Arnold Lesk, Scottsdale, Ariz., assignors to Motorola, Inc., Chicago, Ill.

Continuation-in-part of design applications Ser. No. 120,382, Ser. No. 120,383, and Ser. No. 120,384, all Mar. 2, 1971, all now abandoned. This application Jan. 22, 1973, Ser. No. 325,940

Term of patent 14 years

Int. Cl. D10—07

U.S. Cl. D10—125

Fig. 2

Fig. 3

Fig. 5

FIG. 1 is a plan view of a clock face embodying our new design;

FIG. 2 is a plan view showing a modified form of our design;

FIG. 3 is a plan view showing another modified form of our design;

FIG. 4 is a plan view showing still another modified form of our new design; and

FIG. 5 is a plan view showing a further modified form of our new design.

The clock face is of conventional thickness.

This is a continuation-in-part of co-pending applications Ser. Nos. D. 120,382, D. 120,383, and D. 120,384, all filed Mar. 2, 1971, and now abandoned.

We claim:

The ornamental design for a clock face, as shown and described.
